1

My invention relates in general to electrodynamic machines, and a primary object of the invention is to provide a machine of this general character having a novel and improved commutator structure which renders the machine capable of performing a wide variety of functions.

An important object of my invention is the provision of an electrodynamic machine which is capable of generating electrical components having a wide variety of wave forms ranging from sinusoidal and flat-top waves to intermittent pulsations.

Another important object of my invention is to provide an electrodynamic machine of this character which is capable of generating either direct current or alternating current.

A further object is to provide an electrodynamic machine which is capable of operating as an alternator to generate alternating current in the armature circuit thereof, and which is capable of operating as an induction generator to generate direct current and alternating current, either individually or simultaneously. A related object is to provide an electrodynamic machine which is capable of operating as an induction generator to generate alternating current in the field circuit thereof, and/or direct current in the armature circuit. When operating as an induction generator, the output of the machine may be either direct current or alternating current, or both simultaneously, which is still another object of my invention.

The foregoing objects of my invention, together with various other objects and various advantages which will be apparent hereinafter, may be realized by means of the exemplary embodiments of my invention which are illustrated in the accompanying drawings and which are described in detail hereinafter. Referring to the drawings, which are for illustrative purposes only:

Fig. 1 is a partially schematic view illustrating an electrodynamic machine which embodies the fundamental principles of my invention;

Fig. 2 is a diagrammatic view in the form of a flat development which illustrates the armature winding and the commutator structure of the embodiment shown in Fig. 1;

Fig. 3 is a simplified diagrammatic view illustrating a brush circuit which may be employed in

2

connection with the embodiment of Figs. 1 and 2 when the machine is operating as an alternator;

Fig. 4 is a view illustrating the wave forms and phase relationships of electrical components derived from the brush circuit shown in Fig. 3;

Fig. 5 is a diagrammatic view which is similar to Fig. 3 and which illustrates another brush circuit for use in connection with the embodiment of Figs. 1 and 2;

10 Figs. 6 and 7 are views illustrating the wave forms and phase relationships of electrical components derived from the brush circuit shown in Fig. 5;

Fig. 8 is a diagrammatic view which is similar 15 to Figs. 3 and 5 and which illustrates still another brush circuit;

Figs. 9 and 10 are views illustrating the wave forms and phase relationships derived from the brush circuit shown in Fig. 8;

20 Figs. 11 and 12 are diagrammatic views illustrating circuits for generating various electrical components in connection with the embodiment shown in Figs. 1 and 2;

Figs. 13 and 14 are diagrammatic views illustrating brush circuits which may be employed in connection with the embodiment shown in Figs. 1 and 2 when the machine is operating as an induction generator;

Figs. 15 and 16 are views illustrating the wave 30 forms of electrical components derived from the brush circuits shown in Figs. 13 and 14, respectively;

Figs. 17 and 18 are diagrammatic views illustrating other brush circuits which may be employed when the embodiment of Figs. 1 and 2 is operating as an induction generator;

Figs. 19 to 23 are diagrammatic views illustrating still other brush circuits which may be employed when the embodiment of Figs. 1 and 2 40 is operating as an induction generator;

Figs. 24 to 26 are views illustrating the operation of the machine with the circuits illustrated in Figs. 19 to 21, respectively;

Figs. 27 and 29 are diagrammatic views which 45 are similar to Fig. 2 and which illustrate additional embodiments of my invention; and

Figs. 28 and 30 are views illustrating the wave forms of electrical components which may be generated by the embodiments shown in Figs. 27 50 and 29, respectively.

Referring particularly to Figs. 1 and 2, the embodiment illustrated therein includes a stator 50 which is provided with four pole pieces 51, 52, 53, and 54 of laminated construction in the particular construction illustrated, although any desired number of pole pieces may be employed. The pole pieces 51, 52, 53, and 54 are provided with field windings 55, 56, 57, and 58 thereon respectively, which are connected in series in the particular construction illustrated, the field windings being so arranged that they are adapted to provide alternate north and south poles as indicated by the letters N, S, N and S on the pole pieces 51, 52, 53, and 54, respectively, when the field windings are excited by direct current. The direct current may be supplied to the field windings 55, 56, 57, and 58 through lines 59 and 60 which are connected to a source of direct current such as a battery 61, a switch 62 and resistance 63 being provided in the line 60.

A rotor or armature 65 of laminated construction is mounted in the stator 50 in the conventional manner by means of a shaft and bearings which have been omitted to preserve the clarity of the drawings, the rotor being provided with a plurality of slots 66 therein to receive the conductors of an armature winding 67. As best shown in Fig. 2, the armature winding 67 is a standard wave winding in the particular construction illustrated, the winding including a plurality of terminals which are indicated consecutively by the numerals 71 to 93, inclusive. The characteristic form of the coils of the wave-type armature winding 67 as indicated by the heavy line 95 in Fig. 2, the terminal 71 being connected to the terminal 82 which is in turn connected to the terminal 93 as indicated by the arrows on the heavy line 95. From the terminal 93, the winding 67 leads to the terminals 81, 92, 91, 79, 90, etc., until the winding returns to the terminal 71 as is the conventional practice in wave windings.

The stator 50 and rotor 65 are wound to correspond to the voltage and amperage required, and are wound so that each can function inductively and independently of each other as will be discussed in detail hereinafter. Although the armature winding 67 illustrated is a standard wave winding, any other suitable winding, such as a lap or drum winding, may be employed if desired. The armature winding 67 is preferably a winding having equalized connections of all the terminals thereof which have the same relative potential position, as indicated by the interconnected terminals 71, 82, and 93, in order to increase the winding efficiency in accordance with the conventional practice in armature windings wherein the output is taken from only two brushes.

A commutator 96 is carried by the rotor 65 and is rigidly secured thereto in any suitable manner, the manner in which the commutator is secured to the rotor not being shown specifically in the drawings so that the essential features of the commutator structure may be illustrated more clearly. As best shown in Fig. 2, the commutator 96 includes a plurality of commutator segments which are circumferentially arranged and which are insulated from each other in a manner well known in the art. The commutator segments are arranged in four groups which are indicated by the numerals 97, 98, 99, and 100, each group of segments subtending an angle of 90 degrees, as indicated in Fig. 2, so that the groups 97 and 99 are spaced 180 degrees apart, and the groups 98

and 100 are also spaced 180 degrees apart, the groups 97 and 99 being spaced 90 degrees from the groups 98 and 100. The groups 97 and 99 are symmetrical with respect to each other, and the groups 98 and 100 are also symmetrical with respect to each other, as best shown in Fig. 1.

The group 97 includes a plurality of short segments 101, 102, 103, 104, 105, and 106 which are electrically connected to the terminals 71, 72, 73, 74, 75 and 76, respectively, of the armature winding 67 as best shown in Fig. 2, no identifying numerals having been assigned to the conductors which connect the segments to the winding terminals for the purpose of preserving the clarity of the drawings. The group 98 includes a single long segment 106a which may be connected to the segment 106 of the group 97. The group 99 includes a plurality of short segments 107, 108, 109, 110, 111, and 112 which are connected to the winding terminals 77, 78, 79, 80, 81, and 82, respectively, and the group 100 includes a single long segment 112a which may be connected to the segment 112 of the group 99 the remaining winding terminals, 83 to 93 inclusive, being unconnected.

In the particular construction illustrated, the machine includes four brushes 115, 116, 117, and 118 which are spaced 90 degrees apart, and which engage the commutator 96. Although I have shown four brushes spaced 90 degrees apart, any desired number of brushes and any spacing may be employed depending on the results desired, as will be described in detail hereinafter. As best shown in Fig. 1, the brushes 115, 116, 117, and 118 are connected to conductors 119, 120, 121, and 122, respectively, the brushes 115 and 117 being connected to a load 125 by the conductors 119 and 121. The brush circuit defined by the brushes 115 and 117, the conductors 119 and 121, and the load 125 is intended as illustrative only since a wide variety of brush circuits may be employed as will be discussed in detail hereinafter.

For convenience in illustrating and describing the embodiment of my invention which is shown in Figs. 1 and 2, the number of terminals of the armature winding 67, and the number of commutator segments in the groups 97 and 99 are less than the numbers thereof which are desirable in actual practice. In order to provide greater efficiency and smoother operation, and in order to decrease any commutator ripple, the number of winding terminals and commutator segments employed in actual practice should be greater than the number shown in the drawings as will be appreciated by those skilled in the art.

In general, my electrodynamic machine may be operated either as an alternator, or as an induction generator. When operating as an alternator, the field windings 55 to 58 are excited by direct current so that alternating current is generated at the brushes 115 to 118. When operating as an induction generator, a small current introduced into the armature winding 67 through the brushes 115 to 118 will cause the machine to generate alternating current in the field circuit and direct current at the brushes. In addition to the foregoing general methods of operating the machine, many variations are also possible. The foregoing general methods of operating the machine will be described in detail hereinafter.

In order to understand the operation of my electrodynamic machine, it is necessary that the operation of its commutator structure be thoroughly understood. The operation of the commutator structure may best be understood in

connection with a description of the operation of the machine when operating as an alternator.

Considering the general case wherein the machine operates as an alternator, the field windings 55 to 58 may be excited by direct current from a source such as the battery 61 by closing the switch 62, thereby producing the alternate north and south poles 51 to 54 as previously described. Referring particularly to Fig. 2 and considering the voltage between the brushes 116 and 117, which are spaced 90 degrees apart, it will be noted that the coils of the armature winding 67 which are connected to the brushes 116 and 117 are adjacent each other so that the only voltage between these brushes is equal to the voltage between a pair of adjacent coils, which is very small. The brushes 116 and 117 are short circuited by the long commutator segment 106a so that this small voltage between two adjacent coils is dissipated as in the case of a conventional direct current generator, the net voltage between the brushes 116 and 117 being zero when the armature 65 is in the position shown in Fig. 2 with respect to the brushes. As the armature 65 is rotated by any suitable driving means (not shown) so that the commutator 96 moves from right to left as viewed in Fig. 2 (in the direction indicated by the arrow 130), the brush 116 remains in contact with the long commutator segment 106a for one-quarter of a revolution (90 degrees) of the armature. Meanwhile, the brush 117 successively engages the short commutator segments 107 to 112, inclusive, until at the end of one-quarter of a revolution of the armature 65, the entire space between the brushes 116 and 117 is filled with active coils of the armature winding 67 and the voltage therebetween is a maximum.

As the armature 65 is rotated further, the brush 117 engages the long conductor segment 112a, and remains in engagement therewith until the armature has been rotated through one-half of a revolution (180 degrees). Meanwhile, the brush 116 successively engages the short commutator segments 107 to 112, inclusive, so that the number of active coils between the brushes 116 and 117 is gradually decreased until these brushes are short circuited by the long commutator segment 112a after one-half of a revolution of the armature 65 so that the voltage between the brushes 116 and 117 is again zero.

It will be apparent that the voltage between the brushes 116 and 117 will be a maximum when the armature 65 is in the 90 degree position, i. e., when the armature has rotated through one-quarter of a revolution from the position shown in Fig. 2, since the space between these brushes is then filled with the maximum number of coils of the winding 67. When the armature 65 is in the 90 degree position, the brushes 116 and 117 are in full commutation, the same voltage being generated as would be the case with a conventional wave-wound four pole generator.

Considering the armature position shown in Fig. 2 as the zero degree position, the voltage between the brushes 116 and 117 thus increases from zero at the zero degree position to a maximum at the 90 degree position, and then decreases to zero again after 180 degrees of rotation. As the armature 65 is rotated beyond 180 degrees, the brush 117 successively engages the short commutator segments 101, 102, 103, etc., while the brush 116 remains in contact with the long segment 112a so that after 270 degrees of rotation of the armature, the voltage between

the brushes 116 and 117 is again a maximum. Similarly, after 360 degrees of rotation of the armature 65, the voltage between the brushes 116 and 117 is again zero.

However, after 270 degrees of rotation of the armature 65, the magnetic field in which the active coils between the brushes 116 and 117 are disposed is opposite to the magnetic field in which the active coils between these brushes were disposed after only 90 degrees of rotation of the armature. Consequently, the voltages between the brushes 116 and 117 after 90 and 270 degrees of rotation will be of equal magnitudes but of opposite signs, the voltage in one of these positions being positive, and being negative in the other.

Thus, an alternating voltage is generated between the brushes 116 and 117, the frequency thereof being one cycle per revolution of the armature 65. It will be apparent that the voltage generated between the brushes 117 and 118, which lag behind the brushes 116 and 117 by 90 degrees, will be identical to that generated between the brushes 116 and 117, except that it will lag by one-quarter of a cycle, or 90 degrees. Similarly, the voltages between the brushes 118 and 115 and between the brushes 115 and 116 will also be identical, but will lag by 180 degrees and 270 degrees, respectively.

Thus, the four pairs of brushes which are spaced 90 degrees apart, the brushes 116 and 117, 117 and 118, 118 and 115, and 115 and 116, produce four phases of alternating current, each phase lagging the preceding phase by 90 degrees. The next step in describing the operation of the commutator structure of my electrodynamic machine is to determine the nature of the wave form of the voltage generated between any pair of adjacent brushes, which is the subject of the following paragraphs.

In order to arrive at a mathematical expression for the voltage generated between any pair of adjacent brushes, it shall be assumed that the number of commutator segments comprising the groups 97 and 99 is very large to provide a smooth curve. It shall also be assumed that a coil of the winding 67 which moves past the field poles 51 to 54 at a uniform speed has a voltage generated therein which is of pure sine wave form.

The armature position shown in Fig. 2 with respect to the brushes 115 to 118 shall be considered the starting position, for which $Q=0$, wherein Q is the angle through which the armature 65 has rotated in the direction of the arrow 130. Any conductor of the winding 67 which is disposed midway between adjacent of the poles 51 to 54 is disposed in a magnetic field of zero strength so that the voltage generated in the conductor is zero, such a conductor being indicated by the numeral 131 in Fig. 2 which, although not precisely midway between the poles 51 and 52, may be considered as being midway therebetween for the purposes of this analysis. Thus, when $Q=0$, the voltage generated in the conductor 131 is zero, and when $Q=45$ degrees, this conductor will be disposed opposite the center of the north pole 51 where the magnetic field strength is a maximum so that the voltage generated therein is a maximum. When $Q=90$ degrees, the voltage generated in the conductor 131 will again be zero, etc.

If H =the maximum magnetic field strength, then it will be apparent that the field strength at any position, which shall be indicated by the letter h , will be:

$$h = H \sin 2Q \quad (141)$$

As previously discussed, as the armature 65 rotates beyond the starting point where $Q=0$, active coils of the winding 67 gradually move into the space between the brushes 116 and 117, and the brush 117 successively engages the commutator segments 107, 108, etc. However, as the brush 117 begins to engage the segment 107, the conductors of the coil which is connected to the segment 107 are in a zero field and gradually move into a field of increasing strength as the armature 65 rotates. As the armature 65 continues to rotate, the brush 117 successively engages the segments 108, 109, etc., and the coil which is connected to the segment 107 continues to move into a stronger and stronger field as the space between this coil and its original position becomes filled with the coils which are connected to the segments 108, 109, etc., the latter coils also moving into a field of increasing strength.

Now, if ω is equal to the angular velocity of the armature 65, and t is equal to the time elapsed since the armature was at the starting position where $Q=0$,

$$Q = \omega t \quad (142)$$

At an armature position where $Q=Q_1$, the voltage generated between the brushes 116 and 117 is equal to the sum of the voltages generated in the conductors of the coils disposed between the positions $Q=Q_1$ and $Q=0$. The sum of these voltages may be found by solving a simple differential equation. Letting E equal the maximum voltage generated between the brushes 116 and 117, and letting e equal the voltage therebetween at any time t , the instantaneous voltage when $Q=Q_1$ will be $e=e_1$. As the armature 65 rotates a small additional amount beyond the position where $Q=Q_1$ to a position where $Q=Q_2$, then $e=e_2$. The change in e between $e=e_1$ and $e=e_2$ is due to the addition of conductors of the coils of the winding 67 as the armature 65 moves from $Q=Q_1$ to $Q=Q_2$. Letting the change in e be equal to de , which is proportional to the change in the magnetic field strength h as the armature 65 moves from $Q=Q_1$ to $Q=Q_2$, and letting $Q_2-Q_1=dQ$, then

$$de = Kh \quad (143)$$

where h = the field strength at $Q=Q_2$ and K = the field strength gradient.

In Equation 143, the term Kh represents the number of lines of force cut in a given unit of time t , so that K is not strictly a constant. Letting L equal the length of the conductors of the coils of the winding 67, the number of lines of force in the space between $Q=Q_1$ and $Q=Q_2$ is $LhdQ$. If the number of conductors in a unit angle Q of the armature 65 is equal to C , then CdQ conductors are in the space dQ . However, in order that all of the conductors in the space dQ will cut all of the lines of force in the space dQ , it will be apparent that the armature 65 must rotate through an angle $2dQ$. Consequently, the voltage generated in the conductors in the space dQ as the armature 65 rotates through the angle dQ is equal to one-half the voltage which would be generated if all of the conductors in the space dQ cut all of the lines of force therein. Letting the actual number of lines of force cut by the conductors in the space dQ as the armature 65 rotates through the angle dQ be equal to N , then

$$N = \frac{1}{2} CdQ LhdQ \quad (144)$$

From Equation 142, the time dt required to cut the lines of force in the space dQ as the armature rotates through the angle dQ is equal to dQ/ω , so that the number of lines of force cut per unit time t is N/t , or $N\omega/dQ$, or

$$N/t = CdQ LhdQ \omega / 2dQ$$

or

$$N/t = CL\omega hdQ / 2 \quad (145)$$

Substituting the value of h found in Equation 141, then

$$N/t = HCL\omega \sin 2Q dQ / 2 \quad (146)$$

However, N/t is proportional to the voltage generated by the additional conductors which are made effective as the armature 65 rotates through the angle dQ , which voltage is equal to de as previously stated. Consequently, $de = MN/t$, where M is a constant, so that

$$E = MHCL\omega / 2,$$

where E is a constant representing the maximum voltage generated between the brushes 116 and 117 as previously stated. Thus, substituting this value for E in Equation 146,

$$de = E \sin 2Q dQ \quad (147)$$

Since $\sin 2Q = 2 \sin Q \cos Q$, and substituting this value for $\sin 2Q$ in Equation 147,

$$de = 2E \sin Q \cos Q dQ \quad (148)$$

Integrating Equation 148,

$$e = E \sin^2 Q + C \quad (149)$$

Solving for C in Equation 149, since when $Q=0$, $e=0$, consequently $C=0$.

Thus, the equation for the wave form of the voltage generated between the brushes 116 and 117 is,

$$e = E \sin^2 Q \quad (150)$$

Equation 150 holds for the first 180 degrees of rotation of the armature 65, i. e., from $Q=0$ to $Q=180$ degrees, and since the magnetic field is reversed from 180 degrees to 360 degrees of armature rotation, as discussed previously, the equation for the wave form of the voltage between the brushes 116 and 117 for $Q=180$ degrees to $Q=360$ degrees is,

$$e = -E \sin^2 Q \quad (151)$$

As previously mentioned, the voltages generated between the brushes 117 and 118, 118 and 115, and 115 and 116 are identical to the voltage generated between the brushes 116 and 117 except that they lag by 90 degrees, 180 degrees, and 270 degrees, respectively. The wave forms and phase relationships of these voltages are shown in Fig. 4, the brush connections being indicated in the simplified schematic diagram of Fig. 3. Thus, the voltage phase generated between the brushes 115 and 116 is indicated by the solid curve 155 in Fig. 4, the voltage phase between the brushes 116 and 117 by the dotted curve 156, the phase between the brushes 117 and 118 by the dashed curve 157, and the phase between the brushes 118 and 115 by the dot-dash curve 158, the brush connections for the voltage phases 155, 156, 157, and 158 being indicated diagrammatically by the dimensional arrows 159, 160, 161, and 162, respectively, in Fig. 3.

Considering other wave forms obtainable with my electrodynamic machine, and referring particularly to Fig. 5, a pair of brushes which are spaced 180 degrees apart may be connected to produce a flat-top wave form. For example, if

the brushes 115 and 117 are connected as indicated by the dimensional arrow 165, the resulting wave form will be the algebraic sum of the curves 155 and 156 of Fig. 4. The curves 155 and 156 are also shown in Fig. 6, and the algebraic sum thereof is the dotted curve 166. The curve 166 is a flat-top wave wherein the voltage changes from a maximum negative value to a maximum positive value in 90 degrees of rotation of the armature 65, remains constant at the maximum positive value for the next 90 degrees of rotation, reverses from the maximum positive value to the maximum negative value in the following 90 degrees of rotation, and remains constant at the maximum negative value for the next 90 degrees.

The fact that the curve 166 is flat from 90 to 180 degrees of armature rotation may be shown by considering the equation thereof in this range. From 90 to 180 degrees of rotation, the equation of the curve 155 is Equation 150, i. e.,

$$e = E \sin^2 Q \quad (150)$$

The equation of the curve 156 in this range is,

$$e = E \sin^2(Q - 90) \quad (167)$$

since the curve 156 lags the curve 155 by 90 degrees. Since $\sin^2(Q - 90) = \cos^2 Q$, the equation of curve 156 between 90 and 180 degrees of armature rotation is,

$$E = e \cos^2 Q \quad (168)$$

Consequently, the equation for the curve 166 in this range, letting the voltage of the curve 166 be e_{166} , is,

$$e_{166} = E(\sin^2 Q + \cos^2 Q) \quad (169)$$

or

$$e_{166} = E \quad (170)$$

Similarly, it may be shown that the voltage represented by the curve 166 from 270 to 360 degrees of armature rotation is equal to $-E$.

Referring again to Fig. 5, if the brushes 113 and 116, which are spaced 180 degrees apart, are also connected as indicated by the dimensional arrow 171, a second flat-top wave 172 may be derived which lags the first flat-top wave 166 by 90 degrees as shown in Fig. 7.

The preceding description of the operation of the commutator structure in connection with the operation of my electrodynamic machine as an alternator is based on the relative positions of the brushes 115 to 118 and the poles 51 to 54 which are shown in Fig. 2, or when the brushes are in full commutation. Now consider the brushes 115 and 118 in positions such that the brushes are, in effect, displaced forwardly in the direction of movement of the armature 65 by an angle R with respect to the poles 51 to 54, the brushes being displaced in the direction of the arrow 130, i. e., being located to the left of their positions as shown in Fig. 2. This arrangement is shown schematically in the simplified diagram of Fig. 8.

Assuming that the armature 65 has been rotated through an angle R for convenience so that the relative positions of the brushes 115 to 118 and the commutator 96 are as shown in Fig. 2, the angle through which the armature 65 rotates from this new position will be taken as Q . Following the same procedure as employed previously, the voltage increment between any pair of adjacent brushes, such as the brushes 116 and 117, for example, as the armature 65 rotates through an angle dQ is,

$$de = E \sin 2(Q + R) \quad (173)$$

the angle $(Q + R)$ being the angle through which the armature 65 has rotated from the position shown in Fig. 2 relative to the poles 51 to 54, and the angle Q being the angle through which the armature has rotated from the new brush position as mentioned above. Solving Equation 173 as before, then

$$e = E \sin^2(Q + R) + C \quad (174)$$

Since $e = 0$ when $Q = 0$, as in the preceding case, the constant C in Equation 174 is equal to $-E \sin^2 R$. Consequently, Equation 174 becomes,

$$e = E \sin^2(Q + R) - E \sin^2 R \quad (175)$$

As in the preceding case, Equation 175 holds for $Q = 0$ to $Q = 180$ degrees, and, for $Q = 180$ degrees to $Q = 360$ degrees, becomes,

$$e = -E \sin^2(Q + R) + E \sin^2 R \quad (176)$$

Similarly, the equations for the voltage wave forms of the remaining pairs of adjacent brushes will be identical to Equations 175 and 176, except that these voltage waves will be 90 degrees out of phase with respect to each other as in the preceding case.

It will be apparent that a wide variety of wave forms may be obtained between any pair of adjacent brushes by varying the value of the angle R in Equations 175 and 176. Considering the extreme case where the brushes 116 and 117, for example, are displaced to occupy the positions occupied by the brushes 115 and 116, as shown in Fig. 2, so that the angle $R = 90$ degrees, Equation 175 becomes,

$$e = E \sin^2(Q + 90) - E = E(\cos^2 Q - 1) \quad (177)$$

or,

$$e = -E \sin^2 Q \quad (178)$$

Equation 178 is obviously the equation for the voltage generated by the next pair of adjacent brushes, 117 and 118, which lag the brushes 116 and 117 by 90 degrees.

Considering an intermediate case where $R = 45$ degrees, Equation 175 becomes,

$$e = E \sin^2(Q + 45) - E \sin^2 45 \quad (179)$$

or

$$e = E \sin^2(Q + 45) - E/2 \quad (180)$$

Simplifying, Equation 180 becomes,

$$e = E \sin 2Q/2 \quad (181)$$

As in the previous case, Equation 181 holds for $Q = 0$ to $Q = 180$ degrees, the equation for $Q = 180$ degrees to $Q = 360$ degrees being,

$$e = -E \sin 2Q/2 \quad (182)$$

Equations 181 and 182 also apply to the voltages generated between the remaining pairs of adjacent brushes except that these voltages are 90 degrees out of phase with respect to each other as in the preceding case.

Referring to Fig. 9, the wave form represented by Equations 181 and 182 for the voltage generated between the brushes 116 and 117 is indicated by the dotted curve 185, the curve 185 including two positive pulsations 186 and 187, each of 90 degrees duration, then two negative pulsations 188 and 189, each of 90 degrees duration, then two more positive pulsations, only one of which, 190, is shown, etc. The voltage wave for the lagging pair of adjacent brushes, 117 and 118, is indicated by the dashed curve 191 which is iden-

70

11

tical to the dotted curve 185 except for a 90 degree phase lag, the curve 191 including two negative pulsations 192 and 193, two positive pulsations 194 and 195, etc.

The sum of the two phases 185 and 191 may be obtained by connecting the brushes 116 and 118, as indicated schematically by the dimensional arrow 196 of Fig. 8, this sum being represented by the solid line 197 of Fig. 9. The curve 197 includes a positive pulsation 198 of 90 degrees duration, a no voltage period 199 of 90 degrees duration, a negative pulsation 200 of 90 degrees duration, a no voltage band 201 of 90 degrees duration, a positive pulsation 202 of 90 degrees duration, etc.

By connecting the brushes 115 and 117, as indicated schematically by the dimensional arrow 203 of Fig. 8, as well as the brushes 116 and 118, a curve 204 which is identical to the curve 197 but which lags the latter by 90 degrees, may also be derived as illustrated in Fig. 10. The curves 197 and 204 combined are similar to either of the curves 185 and 191 of Fig. 9 for adjacent pairs of adjacent brushes, except that the magnitude of the pulsations of this combination is doubled over that of the pulsations 186 to 190, or 192 to 195.

It will be apparent that by employing various brush circuits and various values for the brush angle R , a great many wave forms may be derived in addition to those illustrated in Figs. 4, 6, 7, 9, and 10, the number of wave forms possible being limited only by the number of possible brush circuits and brush angle combinations. Some of these wave forms may be useful in electrical therapy. Others are peculiarly adapted to electric hammer operation. Consequently, I do not intend to be limited to the particular wave forms disclosed and the particular applications suggested, since a wide variety of wave forms may be derived, and many applications therefor other than those mentioned will be apparent to persons skilled in the art.

One of the features of my machine when operating as an alternator or as an induction generator, is that the voltage will build up to full load voltage substantially within one revolution. As is well known in the art, conventional generators require many revolutions before the output voltage builds up to full load.

The description of the operation of my electrodynamic machine has thus far been concerned with the operation of the embodiment of Figs. 1 and 2 as an alternator which is capable of generating alternating current when the field windings 51 to 54 are excited by a source of direct current such as the battery 61, my improved commutator structure being responsible for the wide variety of wave forms obtainable at the brushes 115 and 118. As previously stated, the machine is also capable of operating as an induction generator to perform a variety of functions, the operation thereof as an induction generator and the effect of my improved commutator structure on the operation thereof as such being the subjects of the following paragraphs.

Various brush circuits may be employed when the machine is operating as an induction generator, one of these being shown in Fig. 1. The lines 119 and 121 from the brushes 115 and 117, respectively, are connected to the load 125, the brush 117 being connected to a battery 210 by the line 121 and a line 211. The line 122 from the brush 118 is connected to a double throw switch 212 which is movable between two contacts 213 and 214, these contacts being connected to the

12

line 211 on opposite sides of the battery 210. When the machine operates as an alternator, as previously discussed, the switch 212 is in the neutral position shown so that the brush 118 is out of the circuit.

A load 216 may be connected to the lines 59 and 60 of the field circuit by lines 217 and 218, respectively, the line 217 having a switch 219 therein to exclude the load from the field circuit when the machine is operating as an alternator as previously discussed. When the machine is operating as an induction generator, as will be described hereinafter, the switch 219 will be closed, and the switch 62 will be open to exclude the battery 61 from the field circuit.

Considering the operation of the machine as an induction generator with the load 125 in the armature circuit and the load 216 in the field circuit as shown in Fig. 1, moving the switch 212 to the contact 214 will include the battery 210 in the brush circuit, thereby introducing a direct current into the armature winding 67. As the armature 65 is rotated by any suitable driving means (not shown), it will be apparent that the direct current from the battery 210 will create a rotating magnetic field as it flows through the armature winding 67. The speed of this rotating field is equal to the rotational speed of the armature 65, i. e., one cycle per revolution of the armature.

Since the load 216 is in the field circuit, an alternating current will be generated in the field windings 55 to 58 as the lines of force in the rotating magnetic field are cut by the conductors comprising the field windings. The frequency of the alternating current generated in the field circuit is, of course, equal to the rotational speed of the armature 65, i. e., one cycle per revolution of the armature. Since the embodiment illustrated in Figs. 1 and 2 includes four poles, the synchronous speed of the armature 65 is equal to one-half of the frequency of the alternating current generated in the field circuit, comparing the machine to a conventional induction motor.

The alternating current generated in the field circuit produces another rotating field in the field windings 55 to 58, as in the case of a conventional induction motor, so that the polarities of the field poles 51 to 54 are alternately north and south, instead of remaining either north or south as is the case when the field windings are excited by direct current when the machine operated as an alternator. The frequency of the changing polarity of the poles 51 to 54 is determined by the frequency of the alternating current generated in the field circuit, which is in turn determined by the speed of the armature 65, as previously discussed. Consequently, the changing polarity of the poles 51 to 54 is so related to the speed of the armature 65 that a pulsating direct current is generated at the brushes 115 to 118, the frequency of these pulsations being determined by the armature speed. By employing various brush combinations, various wave forms may be derived, the particular brush circuit shown in Fig. 1 being adapted to provide at the load 125 a positive pulsation which is followed by a period of no activity, thence by another positive pulsation, another period of no activity, etc., all as indicated by the curve 220 adjacent the load 125 in Fig. 1.

As previously mentioned, the output of the machine may be divided between the field circuit and the armature circuit in any proportions when operating as an induction generator. For exam-

ple, if each of the field windings 55 to 58 are shorted individually to provide, in effect, a squirrel cage construction, all of the output will be in the form of pulsating direct current in the brush circuit.

The function of the battery 210 in the brush circuit illustrated in Fig. 1 is primarily to start the machine generating, the battery serving as a primer means. The machine will continue to operate inductively in the manner described if the switch 212 is moved to the neutral position illustrated. If the switch 212 is moved to the contact 213 to short circuit the brushes 117 and 118, the machine will stop generating substantially instantaneously and will not start generating again until the switch 212 is again moved to the contact 214 so that the priming operation described previously is repeated.

Since the battery 210 determines the direction of flow of the priming current through the armature winding 67, it will be apparent that if the battery is reversed, the current derived therefrom will merely flow in the opposite direction. The net result of this current reversal in so far as the battery 210 is concerned is that the direct current generated in the brush circuit will be reversed. Consequently, the direct current generated in the brush circuit will always charge the battery 210. Since the direct current generated is pulsating, as indicated by the curve 220 in Fig. 1, the battery 210 within the first one-half of the cycle discharges a relatively small amount of amperage to prime and start the unit to generate inductively in a quick pick up in both voltage and load substantially within one cycle of its armature, and continuous generating shows no indication of any discharge from the battery 210 through oscilloscope observation or meter indication, but is in reverse shows that the unit charges the battery 210 regardless to terminal connections. The charging rate varies proportionally to the battery 210 voltage as shown in curves in Figs. 24, 25 and 26.

The battery 210 is charged, and since the battery controls the direction of current flow, the battery will be charged regardless of how its terminals are connected in the brush circuit. This feature of my invention is shown more clearly in Figs. 13 to 18, inclusive.

Referring particularly to Fig. 13, I show a brush circuit wherein the brushes 116 and 118 are short circuited and are connected to the brush 117 through a battery 225. At A in Fig. 13, I show the directions of current flow during the first one-half (180 degrees) of the operating cycle, and at B I show the directions during the second one-half of the cycle, the flow directions having been obtained with directional ammeters during tests of the machine. The pulsations of the generated direct current corresponding to the portions of the operating cycle shown at A and B in Fig. 13 are shown at A and B in Fig. 15, respectively. Figs. 14 and 16 are identical to Figs. 13 and 15, respectively, except that the battery 225 is reversed, the reversed directions of current flow during the first and second halves of the operating cycle being shown at C and D in Fig. 14, respectively, and the corresponding generated direct current pulsations being indicated at C and D, respectively, in Fig. 16. Thus, regardless of the manner in which the battery 225 is connected in the brush circuit, the battery is always charged by the generated direct current during one-half of the cycle to a greater extent than it is discharged during the other one-half of the cycle.

In Fig. 17, I show a brush circuit wherein the brushes 117 and 118 are short circuited and the brushes 115 and 116 are also short circuited, the two pairs of shorted brushes being connected through a battery 226. At E and F in Fig. 17 are shown the directions of current flow during the first and second halves of the operating cycle, the battery 226 being charged when the directions of current flow are as shown at F. Fig. 18 is identical to Fig. 17 except that the battery 226 is reversed in the brush circuit, the directions of current flow during the first and second halves of the cycle being shown at G and H, respectively. It will be noted that reversing the battery 226 reverses the directions of current flow throughout the brush circuit so that the battery is always charged by the pulsating direct current generated in the armature 65 during one-half of the operating cycle regardless of how the battery is connected. Various brush circuits other than those shown in Figs. 13, 14, 17, and 18 may be employed with similar results.

In Figs. 19 to 21 are shown other brush circuits which are similar to those shown in Figs. 17 and 18, the brushes 115 and 116 being short circuited and the brushes 117 and 118 being short circuited. The shorted brushes 117 and 118 in Figs. 19 to 21 are connected to a switch 236 which is movable between contacts 231 and 232, the contact 231 being connected to the shorted brushes 115 and 116 by a line 233, and the contact 232 being connected to the line 233 through a battery 234. In addition to the battery 234, a variable resistance 235 is connected in the circuit shown in Fig. 19, and an inductance 236 is connected in the circuit shown in Fig. 21. The voltage supplied by the battery 234 regulates the voltage of the alternating current generated in the field windings 55 to 58, and the resistance 235 and inductance 236 vary the relationship between the battery voltage and field voltage as shown in Figs. 24 to 26, which correspond to the circuits shown in Figs. 19 to 21, respectively.

The battery voltage versus field voltage curves shown in Figs. 24 to 26 represent the results of tests conducted with a four-pole, one-quarter horsepower repulsion motor which was reworked to provide the embodiment shown in Figs. 1 and 2. In obtaining these battery voltage versus field voltage curves, all other variables were held constant except that the curves shown in Fig. 24 were obtained with the resistance 235 in the circuit, and the curve shown in Fig. 26 was obtained with the inductance 236 in the circuit. Thus, Fig. 24 illustrates the effect of adding the resistance 235 to the circuit shown in Fig. 20, and Fig. 26 shows the effect of adding the inductance 236 thereto. Referring to Fig. 25, it will be noted that without the inductance 236 or resistance 235 in the circuit, the alternating current voltage generated in the field windings 55 to 58 increases uniformly, whereas with the resistance 235 in the circuit, as shown in Fig. 19, the field voltage is substantially constant at 60 volts as shown in Fig. 24. Adding the inductance 236 to the circuit of Fig. 20 as shown in Fig. 21, does not appreciably affect the relationship between battery voltage and field voltage as may be seen by comparing Figs. 25 and 26. The effect of the resistance 235 and inductance 236 on the direct current generated in the armature 65 to charge the battery 234 may be seen by comparing Figs. 24 to 26, which correspond to the circuits shown in Figs. 19 to 21, respectively. It

should be noted that the armature current values shown in Fig. 24 are in milliamperes whereas the values shown in Figs. 25 and 26 are in amperes.

It will be understood that the test results shown in Figs. 24 to 26 are for the particular size machine employed, and that the results shown will be different for machines of other sizes. Consequently, it will be understood that the results shown are intended as illustrative only, and I do not intend to be limited thereto.

Figs. 22 and 23 illustrate additional brush circuits which may be employed in connection with my electrodynamic machine. In Fig. 22, the brushes 116 and 118 are short circuited and may be connected to the brush 117 by a switch 240 which is movable between two contacts 241 and 242 to include in or exclude from the circuit a battery 243 and an inductance 244. In Fig. 23, the brushes 116 and 118 are also short circuited, and the brush 117 is connected to a switch 250 which is movable between two contacts 251 and 252, the contact 251 being connected to the shorted brushes 116 and 118, and the contact 252 being connected to the brush 115 through a battery 253 and a variable resistance 254. Various other brush circuits may also be employed, some being useful for certain applications, and others being useful for other applications.

An important advantage in including the resistance 254 in the brush circuit shown in Fig. 23 is that the machine will not operate with no load in the field circuit, whereas the machine will operate with no load in the field circuit if no resistance, or only a small resistance is employed.

In Figs. 11 and 12, I show another manner in which my electrodynamic machine is capable of operating as an induction generator. The brushes 115 and 117 are connected to the load 125 as in Fig. 1, and the field windings 55 to 58 are connected to the battery 61, also as in Fig. 1. In Figs. 11 and 12, however, the resistance 63 of Fig. 1 is variable, the resistance of the field circuit being variable by means of a rotatable member 260. The resistance 63 includes a pair of contacts 261 and 262 which are spaced so that when the member 260 disengages the contact 261 and engages the contact 262, the battery 61 is excluded from the field circuit.

When the member 260 is in the position shown in Fig. 11, the resistance of the field circuit is such that the machine operates as an alternator to generate a flat-top wave 263 which is the same as the flat-top wave 166 shown in Fig. 6 and described previously. However, when the member 260 is rotated to the position shown in solid lines in Fig. 12, the resistance of the field circuit becomes such that the dampening effect of the battery 61 is reduced so that the machine may operate partially as an induction generator, thus generating pulsating direct current in the brush circuit as indicated by the curve 264. When moving the member 260 to the contact 262, as indicated in phantom in Fig. 12, so that the battery 61 is excluded from the field circuit and the dampening influence thereof eliminated, the machine operates completely as an induction generator to generate its maximum voltage as indicated by the curve 265 in broken lines. The gap between the contacts 261 and 262 must be such that the member 260 may move from one to the other without opening the field circuit, or the machine would otherwise stop generating. The operation of my electrodynamic machine in this manner results from decreasing and/or

eliminating the dampening effect of the battery 61 on the field circuit so that the machine can operate as an induction generator.

In Figs. 27 and 29, I show embodiments of my invention which are similar to the embodiment shown in Figs. 1 and 2, and which are capable of performing similar functions. The embodiment shown in Fig. 27 includes eight poles 270 having windings 271 thereon which are adapted to produce alternate north and south poles when excited by a source of direct current (not shown). The embodiment of Fig. 27 includes an armature winding 280 having terminals 281 to 305, etc., and includes a commutator 310 having segments 311 to 328, the terminals 281 to 298 being connected to the segments 311 to 328, respectively. Brushes 331 to 334 engage the commutator 310, the brushes being spaced 90 degrees apart.

The segments of the commutator 310 are divided into four groups 335 to 338, each group being of a length such that it subtends an angle of 90 degrees. The segments 311 to 316 of the group 335, and the segments 320 to 325 of the group 337 are one-half the length of the segments 317 to 319 and 326 to 328 of the groups 336 and 338, respectively.

Fig. 28 illustrates one of the wave forms which may be derived when the embodiment of Fig. 27 is operating as an alternator, i. e., with the field windings 271 excited by direct current. Various other wave forms may also be derived as discussed previously, and this embodiment is also capable of operating as an induction generator in the manner discussed previously.

The embodiment shown in Fig. 29 includes four poles 340 having windings 341 thereon which are adapted to produce alternate north and south poles when connected to a source of direct current (not shown). This embodiment includes a field winding 350 having terminals 351 to 375, etc., and includes a commutator 380 having segments 381 to 392, the terminals 351 to 362 being connected to the segments 381 to 392, respectively. Brushes 393 to 396 engage the commutator 380, the brushes being spaced 90 degrees apart.

The segments of the commutator 380 are divided into four groups 397 to 400, the groups 397 and 399 each subtending an angle of 45 degrees, and the groups 398 and 400 each subtending an angle of 135 degrees. The segments 381 to 383 of the group 397, and the segments 387 to 389 of the group 399 are one-third the length of the segments 384 to 386 and 390 to 392 of the groups 398 and 400, respectively.

Fig. 30 illustrates one of the wave forms which may be derived when the embodiment of Fig. 29 is operating as an alternator, i. e., with the field excited by direct current. The wave form shown is a 45 degree flat-top wave with 135 degree reversal gradients. Various other wave forms may also be derived, and this embodiment may also be operated as an induction generator as previously described.

Thus, my invention provides an electrodynamic machine which may be employed either as an alternator or an induction generator. Since various embodiments of the machine other than those disclosed herein may be employed without departing from the spirit of the invention, and since the machine is susceptible to applications other than those mentioned herein, I do not intend to be limited to the specific disclosures contained herein, but desire to be afforded the

protection offered by the full scope of my appended claims.

I claim as my invention:

1. In an electrodynamic machine of the character described, the combination of: relatively movable primary and secondary members; a winding on said primary member; an armature winding on said secondary member, said armature winding including a plurality of successive terminals; a commutator including a plurality of mutually insulated successive segments which are connected to the respective successive terminals of said armature winding, the length of one of said segments being substantially greater than the length of the remaining segments; and brushes engaging said commutator.

2. In an electrodynamic machine of the character described, the combination of: relatively movable primary and secondary members; a winding on said primary member; an armature winding on said secondary member, said armature winding including a plurality of successive terminals; a commutator including a plurality of successive mutually insulated segments which are connected to the respective successive terminals of said armature winding, said segments being arranged in groups of one or more successive segments, the length of said segments comprising one of said groups being substantially greater than the length of said segments comprising another of said groups; and brushes engaging said commutator.

3. In an electrodynamic machine of the character described, the combination of: a stator having a multipole field winding; a rotor having a winding which includes a plurality of terminals; a commutator carried by said rotor and including a plurality of segments which are arranged in a plurality of pairs of circumferentially arranged groups, said groups of one of said pairs being spaced 180 degrees apart, and said groups of another of said pairs being spaced 180 degrees apart and being disposed between said groups of said one pair, said segments comprising said groups of said other pair; means connecting successive terminals of said rotor winding to successive segments of said groups; and brushes engaging said commutator.

4. In an electrodynamic machine of the character described, the combination of: a stator having a multipole field winding; a rotor having a winding which includes a plurality of terminals; a commutator carried by said rotor and including a plurality of segments which are connected to said terminals of said rotor winding, said segments being arranged in a plurality of pairs of circumferentially arranged groups, said groups of one of said pairs being spaced 180 degrees apart, and said groups of another of said pairs being spaced 180 degrees apart and being disposed between said groups of said one pair, said segments comprising said groups of said one pair being longer than said segments comprising said groups of said other pair; and brushes engaging said commutator.

5. An electrodynamic machine as defined in claim 4 wherein said pairs of groups are two in number, and wherein the lengths of said segments are such that each of said groups subtends an angle of 90 degrees.

6. An electrodynamic machine as defined in claim 4 wherein said pairs of groups are two in number, wherein each of said groups of said one pair comprises a single segment of a length such

that it subtends an angle of 90 degrees, and wherein each of said groups of said other pair comprises a plurality of segments of a length such that each of said groups of said other pair subtends an angle of 90 degrees.

7. An electrodynamic machine according to claim 4 including variable resistance means in series with said field winding.

8. In an electro-dynamic machine of the character described, the combination of: relatively movable primary and secondary members; a winding on said primary member forming a series of poles, successive poles being of opposite polarity; an armature winding on said secondary member, said armature winding including a plurality of conductors arranged about the periphery of said secondary member, said conductors being connected in series, a group of adjacent conductors extending over a substantial portion of said periphery being provided with corresponding terminals; a commutator including a plurality of circumferentially arranged segments, the lengths of some segments being substantially greater than the lengths of other segments; conductor leads connecting successive terminals of the armature winding to successive commutator segments including some commutator segments of greater length and some of lesser length; and brushes engaging said commutator.

9. An electro-dynamic machine as defined in claim 8 in which said portion is greater than about the angular spacing between successive poles and the ends of said group are separated by an angular distance greater than about the spacing between adjacent poles.

10. In an electro-dynamic machine of the character described, the combination of: relatively movable primary and secondary members; a winding on said primary member forming a series of poles, successive poles being of opposite polarity; an armature winding on said secondary member, said armature winding including a plurality of conductors arranged about the periphery of said secondary member, said conductors being connected in series, a group of adjacent conductors extending over a portion of said periphery equal to more than about the spacing between successive poles being provided with corresponding terminals; a commutator including a plurality of segments arranged in a plurality of circumferentially arranged groups, the lengths of the segments comprising one of said groups being substantially greater than the length of the segments comprising another of said groups, successive terminals of the armature winding being connected to successive commutator segments including some commutator segments of said one group and some of said another group; and brushes engaging said commutator.

11. An electro-dynamic machine as defined in claim 10 in which said groups of commutator segments extend over angular distances equal to at least about half the angular spacing between poles.

12. An electro-dynamic machine as defined in claim 10 in which said groups of commutator segments extend over angular distances equal to at least about the angular spacing between poles.

13. In an electro-dynamic machine of the character described, the combination of: relatively movable primary and secondary members; a winding on said primary member forming a series of poles, successive poles being of opposite polarity; an armature winding on said secondary member, said armature winding including a plural-

ity of conductors arranged about the periphery of said secondary member, said conductors being connected in series, a plurality of said conductors over a substantial portion of said periphery being provided with corresponding terminals; a commutator including a plurality of circumferentially arranged segments, successive segments being connected to successive terminals, the angular spacing between some of the interconnected terminals and segments being substantially greater than the angular spacing between other interconnected terminals and segments; and brushes engaging said commutator.

14. An electro-dynamic machine as defined in claim 10 in which the difference between said angular spacings is at least equal to about half the angular spacing between successive poles of the primary member.

15. An electro-dynamic machine as defined in claim 10 in which the difference between said angular spacings is at least equal to about the angular spacing between successive poles of the primary member.

16. A multipolar electro-dynamic machine as described, comprising a stator wound with $2N$ alternate polarity fields (where N is any whole number not less than 2), a rotor provided with a uniformly distributed winding, a commutator provided with a plurality of angularly spaced segments, said segments being divided into groups, successive segments of one of said groups being uniformly connected to successively separated points on said rotor winding of corresponding angular displacement, successive segments of a second one of said groups being uniformly connected to successively separated points on said rotor winding spaced a distance substantially equal to a pole arc from said first named points, successive segments of third and fourth groups being non-uniformly connected to successively separated points on said rotor winding between said first and second named groups, there being a group of successive points on said rotor winding corresponding to an arc of two poles unconnected to said commutator, and collector brushes in contact with said commutator whereby to derive flat top peak potential alternating current, through a pair of said brushes 180 degrees displacement and multiple phase cyne alternating current between pairs of said brushes at 90 degrees displacement.

17. A multipolar electro-dynamic machine described, comprising a stator having a plurality of alternate polarity fields, a rotor provided with a distributed winding, a commutator provided with a plurality of angularly displaced segments, said segments being divided into groups, successive segments of one of said groups being connected to successively separated points on said rotor winding, the successive segments of a second one of said groups being connected to successively connected points on said rotor winding spaced a distance substantially equal to a pole arc from said first named points, there being a group of successive points on said rotor winding unconnected to said commutator, a plurality of brushes for said commutator whereby said fields are adapted to be inductively excited by said rotor to cause generating alternating current in said field winding when a pair of said brushes are short circuited and in circuit with a direct current battery priming source through a further intervening brush of said brush groups wherein said priming battery takes a self adjusting charge

regardless of terminal connection of said brush circuit.

18. A multipolar electro-dynamic machine as described, comprising a stator having a plurality of alternate polarity fields, a rotor provided with a distributed winding, a commutator provided with a plurality of angularly displaced segments, said segments being divided into groups, successive segments of one of said groups being connected to successively separated points on said rotor winding, the successive segments of a second one of said groups being connected to successively connected points on said rotor winding spaced a distance substantially equal to a pole arc from said first named points, there being a group of successive points on said rotor winding unconnected to said commutator, a plurality of brushes for said commutator whereby said fields are inductively excited by said rotor and to generate alternating current in said field winding and generating direct pulsating current through pairs of said brushes in load when primed through a further intervening brush of said brush groups in circuit with a storage battery and said loaded pair of brushes and further means to destroy inductive generating by short circuiting said control brushes through a switch that omits the said battery.

19. A multipolar electro-dynamic machine comprising: a stator having a plurality of alternate polarity fields; a rotor provided with a distributed winding; a commutator provided with a plurality of angularly displaced segments; said segments being divided into groups; successive segments of one of said groups being connected to successively separated points on said rotor winding; the successive segments of a second one of said groups being connected to successively connected points on said rotor winding spaced a distance substantially equal to a pole arc from said first named points; there being a group of successive points on said rotor winding unconnected to said commutator; a plurality of brushes for said commutator by which said fields are caused to be inductively excited by said rotor so as to generate an alternating current in said field windings when a plurality of said brushes are short circuited; and a priming circuit including a storage battery connected to a plurality of said brushes to enable a relatively weak current from said battery to cause the machine to generate.

20. A multipolar electro-dynamic machine comprising: a stator having a plurality of alternate polarity fields; a rotor provided with a distributed winding; a commutator provided with a plurality of angularly spaced segments; said segments being divided into a predetermined number of groups; successive segments of the first of said groups being connected to successively separated points on said rotor winding of corresponding angular displacement; the segments of a second of said groups being successively connected to points on said rotor winding of different angular displacement than the segments of said first group; the segments of the third and fourth groups being connected to said rotor winding similarly to said first and second groups at points of opposite polarity; a plurality of brushes for said commutator including a pair of short-circuited brushes arranged a predetermined number of degrees apart; a priming circuit including a storage battery and certain of said brushes; and means for stopping generating of current in

the machine by excluding said battery from the priming circuit.

21. A multipolar electro-dynamic machine comprising: a stator having a plurality of alternate polarity fields; a rotor provided with a distributed winding; a commutator provided with a plurality of angularly spaced segments; said segments being divided into a plurality of groups; successive segments of the first of said groups being connected to successively separated points on said rotor winding of corresponding angular displacement; the segments of a second of said groups being successively connected to points on said rotor winding of different angular displacement than the segments of said first group; the segments of third and fourth groups being connected to said rotor winding similarly to said first and second groups at points of opposite polarity; a plurality of brushes for said commutator; a first pair of brushes shortcircuited at 180 degrees apart; a second pair of brushes arranged 180 degrees apart and at 90 degrees displacement from said shortcircuited brushes; a storage battery; said second pair of brushes being in circuit with said storage battery; a resistor in said circuit, whereby to produce alternating current in said stator and pulsating direct current in said circuit adapted to charge said battery regardless of the manner in which the terminals thereof are connected in the brush circuit; and means for stopping generating of current in said stator and rotor by shortcircuited one brush of said second pair of brushes and excluding said battery from the circuit.

22. A multipolar electro-dynamic machine comprising: a stator wound with $2N$ alternate polarity fields (where N is any whole number not less than 2); a rotor provided with a uniformly distributed winding; a commutator provided with a plurality of angularly spaced segments; said

segments being divided into groups; successive segments of one of said groups being uniformly connected to successively separated points on said rotor winding of corresponding angular displacement; successive segments of a second one of said groups being uniformly connected to successively separated points on said rotor winding spaced a distance substantially equal to a pole arc from said first named points; successive segments of third and fourth groups being non-uniformly connected to successively separated points on said rotor winding between said first and second named groups; there being a group of successive points on said rotor winding corresponding to an arc of two poles unconnected to said commutator; collector brushes in contact with said commutator, by which said fields are caused to be inductively excited by said rotor so as to generate an alternating current in said field windings when a plurality of said brushes are short circuited; and a priming circuit including a source of direct current connected in the brush circuit to enable a relatively weak current from said direct current source to cause inductive generating of the machine.

CLINTON H. HULBERT.
